(57) **CLAIM**

We claim the ornamental design for a barcode scanner, as shown and described.

DESCRIPTION

FIG. 1 is a perspective view of a barcode scanner showing our new design from the front, top, and left side;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are directed to features of the barcode scanner that form no part of the claimed design.
